UNITED STATES PATENT OFFICE.

ERNEST BERTRON, OF BRUSSELS, BELGIUM.

TELEPHONIC AND RADIOTELEPHONIC MESSAGE OR AUDITION BY MEANS OF FLUID RESISTANCE.

Application filed August 24, 1923. Serial No. 659,070.

To all whom it may concern:

Be it known that I, ERNEST BERTRON, a citizen of France, residing at Brussels, Belgium, have invented certain new and useful 5 Improvements in Telephonic and Radiotelephonic Messages or Auditions by Means of Fluid Resistance, of which the following is a specification.

The object of the present invention is a 10 method for improving the messages sent by telephone or wireless telephone, and the auditions (concerts or the like) given by the same means, in order to obtain, on one part, a refinement or a sort of filtering of the received sounds by eliminating any parasite 15 noises and, on the other part, to permit the audition by such a large number of listeners as may be desired, without the sound perceived by every one of them being weakened.

20 This method consists essentially in switching in the telephonic circuit, or in the wireless reception circuit, one or several liquid resistances of any suitable form and dimensions.

25 This method will permit to have the same audition listened to by a very large number of persons, by connecting any desired number of receivers in parallel on one of the liquid resistances of the circuit.

30 The invention moreover contemplates an appliance for the realization of said method.

In order that the following description 35 may be more easily understood, same will refer to the appended drawings which show a practical embodiment of the invention, given as example.

Fig. 1 illustrates an installation according, 40 to this invention for a telephonic audition.

Fig. 2 is a modification of same. 45 Figs. 3-4-5-6 illustrate several forms of execution of an appliance for receiving wireless auditions.

Fig. 7 illustrates an installation used for 50 permitting a large number of persons simultaneously listening to a wireless audition, by connecting an intermediate telephonic circuit.

In Fig. 1, 1 and 2 are the two wires of a 55 telephonic circuit, whilst the microphone in front of which the sounds are emitted, is located at any suitable distant point.

One of said wires, such as 1, is connected 60 to a container 3 enclosing a suitable conducting liquid, such as water.

With the other wire 9 are connected any 55 desired number of conductor-wires 4, 4', 4'' etc. each being coupled with a receiver such as 5, 5', 5'' etc.

This circuit of every receiver shall be closed by dipping the end of the return-wire 60 6, 6', 6'' etc. of same in the liquid in container 3.

The several wires 6, 6', 6'' etc. can be provided at their ends with small balls, or other suitably shaped parts 7, 7', 7'' etc. made of an insulating material through which is passed the naked end of the corresponding wire. Said insulating parts 7 are intended 65 to avoid any prejudicial contact between the ends of the several wires 6, 6', 6'' or between 70 said wires and the other points of the circuit.

The circuit of every receiver shall be closed when required, by dipping into the liquid, the corresponding part 7. Same can 75 be of the desired density either to float on, or to sink into the liquid, as required.

Now, a given number of persons being placed around container 3, every one can bear one of the receivers to her ears, but shall 80 hear nothing. However, by dipping into the liquid the part 7 corresponding to her receiver, each of them will close the circuit and hear clearly the sounds emitted before 85 the distant microphone.

It will thereby be possible to have a number 90 of listeners equal to the number of receivers, i. e. as large as can be desired, to hear any given audition.

For making the installation more easy, 95 the arrangement shown as example in Fig. 1, can be resorted to. The cup-shaped or other suitable container 3, is located on a table, or other suitable article of furniture 8, the foot of which is hollowed for the passing 95 of the circuit-wires.

One of said wires, such as 1, passes through the table and ends in the container 3. The other wire may be coiled around the table 100 provided with hooks 10 for hanging the idle receivers, as shown in the drawing.

When required, several similar devices can 105 be shunted on the same circuit. Also, several ones can be connected in series with one and the same circuit, as seen in Fig. 2.

The operation is the same in every case. The number of containers 3 can thus be increased at will, and so large a number of

listeners as desired can be placed around every container, without the receiver sound being weakened.

In addition to the above advantages, and 5 the possibility of having the audition heard by any large number of persons at the same time on the other part, the foregoing arrangement presents the advantage of an attractive character owing to the mystery of 10 the auditions to persons nonconversant with its working.

In fact, for every listener, it seems as if 15 the perceived sounds were emitted in the liquid enclosed in container 3. Said liquid has thus apparently acquired the peculiarity of singing, speaking etc. which enticed the inventor to give this method and appliance the name of "singing-water."

Of course, any conducting-liquid may be 20 used. The intensity of the perceived sounds increases with the conducting-power of the liquid. Goods results can be obtained by the use of plain water; distilled water weakens the sounds, whilst same will be 25 stronger when some acid, basic, or salt electrolyte is dissolved in the water.

The grouping of the several receivers connected to the liquid resistances, permits of 30 forming a whole giving the same results as the "loud talker" without having its disadvantages, the chief advantage being that the useful sounds alone are strengthened, but not the extraneous sound, as occurs with 35 the "loud talkers."

One of the receivers can be at will, replaced by a loud talker connected with the 40 liquid resistance, the sounds thus emitted by said "loud talker" being improved by the refinement or filtering through the liquid resistance.

The method according to this invention, can also be resorted to for receiving wireless 45 messages. It will be sufficient to switch into the circuit of the receiver or receivers, one or several liquid resistances of suitable shape. The same refinement and filtering of the sounds will be obtained. Figs. 3-4-5-6 illustrate an example of embodiment of this 50 method. 11 is the amplifier; 12 and 13 the wires in connection with the receiver.

In one of said wires (Figs. 3 and 4) or in both, (Figs. 5 and 6) are switched one or 55 several liquid resistances, that can be made of tubes 14 enclosing a suitable conducting liquid, or of containers 15 of any suitable shape.

It will always be possible, by adequately proportioning the volume of liquid, or by suitably choosing said liquid (pure water, distilled water or electrolytic solution) to graduate or variate at a leisure, the quality 60 of the received emissions.

The method of this invention can also be 65 used when it is desired to have a large number of persons hearing a wireless audition

without resorting to the "loud talker." It will then be sufficient to locate the wireless-receiver in front of a microphone connected with a telephonic circuit comprising one or several of the arrangements described in 70 reference with Figs. 1 and 2.

The arrangement illustrated as example in Fig. 7 can be resorted to.

The receiver 16, switched on the wireless-receiving circuit, of which 11 is one of the 75 amplifiers, is located in front of a microphone 17 connected with a telephone-circuit enclosing one, two or more of the above described liquid resistances.

It is thus possible to have any large number of persons hearing the radiograms, 80 concerts, auditions or the like, received by the wireless-telephonic apparatus on which the receiver is switched.

The same results are obtained as when 85 using a loud talker, but without alteration of the audition or increase of the extraneous sounds, as is the case with the loud talker.

The wireless receiver 16 can be disposed 90 on the end of a bar 18 moveable on a slide 19 and allowing any desired adjustment of the distance between the wireless-receiver and the microphone.

The inventor insists that above described 95 arrangements are merely given as examples and without limiting the scope of this invention.

Claims:

1. The method of improving the telephonic or wireless messages auditions, 100 concerts, and the like transmitted in an electric circuit, consisting in introducing in series into the circuit of a receiver or receivers one or more liquid resistances.

2. In receiving telephonic wireless or like 105 auditions by means of an electric circuit; the combination of liquid resistances connected in the circuit in series and a number of receiver circuits each including a terminal for insertion into the liquid resistance to complete the circuit in order to allow a large 110 number of persons to hear the audition simultaneously.

3. An appliance for telephonic audition 115 by a large number of persons comprising a telephonic circuit, a container adapted to enclose a conducting liquid in which one of the wires of the telephonic circuit terminates; a microphone in the circuit in front of which the sound (such as a concert) is emitted, a number of receivers each connected in a circuit with the second wire of the telephonic circuit on one side and with the liquid resistance at the other side whereby several of said containers can be connected in shunt and others in series in one 120 and the same circuit.

4. In an appliance as set forth in claim 125 3; means for closing the circuit of each receiver by dipping one of the wires connected 130

with the receiver into the liquid, such wire being provided at its end with a terminal part made of insulating material that can be placed in the liquid leaving the adjacent end of the wire exposed for making contact with the liquid.

5. In an appliance as set forth in claim 3; a suitable article of furniture for supporting the liquid container in which are hidden

the circuit wires one of which terminates in ¹⁰ the container in contact with the liquid, and means for completing the listening circuits by placing a terminal thereof in the liquid in the container in order to give the listeners the illusion that the container has the gift ¹⁵ of emitting the sounds.

In testimony whereof I affix my signature.

ERNEST BERTRON.
